(57) **CLAIM**

The ornamental design for a bone fixation pin as shown and described.

DESCRIPTION

FIG. 1 is a perspective view of a bone fixation pin, according to our new design;

FIG. 2 is a second perspective view of a bone fixation pin thereof;

FIG. 3 is a side view of a bone fixation pin thereof;

FIG. 4 is a side view of a bone fixation pin thereof;

FIG. 5 is a back view of a bone fixation pin thereof;

FIG. 6 is a front view of a bone fixation pin thereof;

FIG. 7 is a side view of a bone fixation pin thereof; and,

FIG. 8 is a side view of a bone fixation pin thereof.
